UNITED STATES PATENT OFFICE.

JOHN H. SUTTER, OF CHICAGO, ILLINOIS.

LAUNDRY MACHINERY.

1,092,605.

Specification of Letters Patent.

Patented Apr. 7, 1914.

Application filed November 21, 1908. Serial No. 463,758.

To all whom it may concern:

Be it known that I, JOHN H. SUTTER, a citizen of the United States, residing at the city of Chicago, in the county of Cook and State of Illinois, have invented a new and useful Improvement in Laundry Machinery, of which the following is a specification.

My invention relates to washing and rinsing machines for use in domestic and public laundries.

My invention is adapted to meet the conditions in public laundries where a machine of limited capacity is desirable, and also to provide for domestic use a mechanism which has the conveniences which are necessary in commercial practice. To this end I provide a rotating or reciprocating tub and connections by which the cleansing fluids may be readily introduced into or drained therefrom, and while in operation, if desired.

My invention also comprises mechanism for giving such form and action to the parts that the application of the cleansing fluids is active and efficient.

The principles of my invention are illustrated in the drawings in which—

Figure 1 shows a front view; Fig. 2 a side elevation, partly in section; Fig. 3 is a sectional view taken on the dotted line 3—3 of Fig. 2; Fig. 4 is a sectional view of the lower part of the hollow shaft and its connections; Fig. 5 is a top view of the spring buffer connections; Fig. 6 is a section of Fig. 5 on the dotted line 6—6. Fig. 7 is a section of Fig. 2 on the dotted line 7—7; Fig. 8 is an enlarged detail partly in section on the line 8—8 of Fig. 7; Fig. 9 is a clutch shifting device for the main shaft; Fig. 10 is a portion of the washer head arm; Fig. 11 shows a detail of an adjustable fastening by which a handle is attached to the arm of clutch lever 43; Fig. 12 is a top view of the center of the tub bottom. Fig. 13 shows the detail of a shaft geared to the motor, and its alternatively engageable connections.

Further describing my invention with reference to the drawings, in which like characters of reference denote like parts throughout: 1 represents a bed or table; 2, 3 and 4 are uprights which support the table and of which 3 and 4 are extended upwardly for the purposes hereinafter described. A hollow vertical shaft 6 is journaled at its lower

end in the stuffing box 7 and is supported within the chamber below such stuffing box 55 upon the stud 8. The said shaft passes upwardly through the table 1 and is provided with a taper joint or other suitable connection, by which it is secured to the spider 9, having the arms 10, upon which is supported 60 the tub 11. The latter is perforated at the center of the bottom and a fluid tight connection is made between the inside of the tub and the vertical shaft 6. The lower part of the spider is provided with a hub 12, having projecting lugs 13. The said hub projects downwardly into the interrupted sleeve 14, from which project the arms 15. The said sleeve and arms are concentrically mounted on the shaft 6 so that the lugs 13 of 70 the spider are within the notches formed in the sleeve, and the said arms are connected by springs 16 to the table or frame work of the apparatus. An arm 18 is keyed to the lower part of the shaft 6 and on the latter 75 preferably upon a sleeve 19, upwardly projecting from said arm, is mounted a collar 20, from which project the arm 21 and the crank 22. A vertical shaft 23 is carried on the bracket 26 and the cross-piece 27, the 80 latter being supported on the upper part of the uprights 3 and 4. It is provided with the worm gear 28, inclosed in the gear case 29, and meshing with the gear is a worm 30 on the shaft 31, driven by the motor 34, controlled by the switch 34'. On the lower part of the said shaft 23 is a crank 32, which is connected by the pitman 33 with the crank 22. The crank 32 is much shorter than the crank 22, whereby the complete revolution of 90 the former gives a reciprocating motion to the latter, which in turn is communicated to the tub as hereinafter described.

The crank 32 is feathered on the shaft 23, and the shaft is provided with a clutch 35 95 which, when the shaft is dropped, will be out of engagement with the crank and its connections. Upon the cross-piece 27 is mounted a wringer 36, having its rolls 100 geared together in the usual manner. Upon an extension of one of the shafts 37 is carried a beveled gear 38 meshing with a corresponding gear 39, which is normally free from engagement with the shaft 23. The gear 39, however, is provided with notches 105 into which the cross pin 40 will seat when

the shaft 25 is in its downward position. A shifting device consisting of the grooved pulley 41, the crutch 42 and the lever 43, provides means by which the shaft 25 may be longitudinally moved to alternatively engage with the crank 32 and the gear 39.

43' is a movable stud by which the lever 43 is detachably secured in alternative position.

10 Pipes 45 controlled by the valves 46 connect with any source of hot and cold water supply communicate through the common pipe 47 with the chamber 48, within which rests the lower end of the vertical shaft 6, which 15 is provided with the openings 49. A similar connection, within said chamber, is made by the pipe 50, which may be connected with the leg 2 and controlled by the outlet or discharge valve 51.

20 The lower part of the tub 11 should be slanted toward the center as shown in Fig. 2 and the lower part thereof should be provided with radial slats 55 which are vertically wider near the center of the tub than 25 at their other end and which are adapted to keep the material to be cleansed out of contact with the bottom of the tub. The upper edges of slats 55 should be substantially horizontal so as to form spaces which are 30 deepest at the center of the tub and provide a protected fluid receptacle. A washer head arm 57 may be hinged to one of the uprights and the free end thereof has a squared opening through which passes the rectangular 35 bar 58 which sockets removably in the washer head 59. The said bar has free vertical motion so that the washer head may rest upon the material in the tub. It may, however, be readily lifted out and the arm 40 57 swung free from the tub.

When it is desired to operate the washing apparatus, the material to be cleansed is placed in the tub with such cleansing agents as may be desired, and water of the properly 45 regulated temperature turned thereinto through the tubes 45 and the hollow shaft 6. The washer head being placed in position upon the material, the motor may be started, whereby the shaft 25 (being placed in gear 50 with the crank 32) is caused to revolve. The latter gives reciprocating motion to the crank 22, through the pitman 33 and the motion thereof is communicated through the coiled spring 21' to the arm 18. The inter- 55 position of the spring causes the rapid motion of the crank to be communicated to the tub without shock. When the tub has made a partial revolution the lugs 13 will come into contact with the projecting sleeve portions 14, thereby tensioning the springs 16. The shock of stopping the rotation of the tub is thus absorbed by the springs and the rotation comparatively slowly stopped. The tension of the spring, however, being ap- 65 plied, starts the tub on its return movement,

after which the action of the power through the arms 21 and 18 and the spring 21' is again applied in the other direction, until upon approaching the limit of its movement the springs 16 again absorb the shock and start the tub in the first direction. It will be noted that the fluids in the tub are normally moved by centrifugal action to flow between the radial slats of the bottom of the tub toward the sides thereof, and the tendency to remain at rest forces them through the material adjacent to the edge of the tub in a direction opposite to its initial movement. When the tub reverses under the stress of the spring 16 the tendency of the fluids is to reverse their direction, both through the material adjacent to the sides of the tub and following the slanted bottom thereof toward the center. These initial movements of fluids throughout the material within the tub set up other currents dependent thereupon and the whole exercise a powerful cleansing and detergent action thereon. When the action of the tub has been continued as far as desired the escape valve 51 may be opened, allowing the fluids to escape, while fresh fluid of the proper temperature may be introduced and its flow continued during the continuous operation of the machine until a sufficient amount has been admitted and the fluid may be alternately introduced and discharged, until the material is thoroughly rinsed and cleansed. The washer head is then removed, the vertical shaft 25 dropped by the shifting mechanism, whereby the washer is disconnected, and the wringer put in motion, by which the process is completed.

I claim:

1. In a laundry machine; the combination of a frame or support, a hollow shaft journaled vertically therein, a washing and rinsing tub mounted on the upper end of the shaft and rotatable thereby, means for giving alternating rotary movement to the shaft, and fluid connections opening into the tub through said shaft and adapted to provide a flow of fluid to and from the tub during the movement of the shaft. 105

2. In a laundry machine; a supporting structure, a hollow shaft journaled therein, a washing and rinsing tub provided with a sloping bottom mounted on the shaft and opening thereinto, means for keeping the material to be cleansed out of contact with said bottom, and forming radial channels for fluid, means for introducing fluid into said channels through the hollow shaft, and means for giving alternating rotary movement to the shaft. 115

3. In a laundry machine, a supporting framework including tubular members adapted to be connected with a source of water supply and a discharge outlet, a tub mounted on a hollow shaft opening into the said tub 120 125 130

and also opening into said tubular members, means for actuating said shaft to operatively move the tub, and means for regulating the supply of fluid to the tub through said tubular members and said shaft during the operation thereof.

In witness whereof, I have hereunto set

my hand, this 18th day of November A. D. 1908, in the presence of two subscribing witnesses.

JOHN H. SUTTER.
